TO GENERAL RAILWAY SIGNAL COMPANY, OF GATES, NEW YORK, A CORPORATION
OF NEW YORK.

INDIVIDUAL CALLING-KEY.

1,105,766.

Specification of Letters Patent.

Patented Aug. 4, 1914.

Application filed May 10, 1911. Serial No. 626,285.

To all whom it may concern:

Be it known that we, MAURICE F. GEER and RICHARD C. LEAKE, citizens of the United States, and residents of the city of 5 Rochester, in the county of Monroe and State of New York, have invented a new and useful Individual Calling-Key, of which the following is a specification.

This invention relates to an individual 10 calling key and especially to an individual calling key for use in a system of selective signaling in which all energy is supplied from a central station.

The primary object of this invention is to 15 so construct an individual calling key of the kind described, that it will not only govern impulses of electricity sent to a pair of line wires, but it will also govern the starting and stopping of a generator to furnish current for said impulses.

A further object of the invention is to so 20 construct an individual calling key of the nature described that it may be adjusted so as to send out any desired number of impulses of any desired polarity, within its range.

A further object of the invention is to so 25 construct an individual calling key of the nature described that a call may be made with a minimum of effort and attention.

A further object of the invention is to so 30 construct a calling key of the nature described, that a plurality of the same may be assembled to any desired extent depending upon the number of stations on a line.

The invention consists of means for attaining the hereinbefore stated objects and others, which will later appear as the description of the physical embodiment used 35 to illustrate our invention, progresses.

At the present time there are two general methods in use for operating selective signaling systems, distinguished one from the other by the mode of supplying electrical 40 energy for the operation of the system. The first method, called the "local energy system," employs batteries located at each station where a selector is located, for the purpose of supplying electrical energy for the 45 operation of a signaling device which is caused to operate by the operation of the

selector. The second method, called the "central energy system," employs no batteries at the local stations but supplies all energy needed for the operation of the system from the central station. The central energy systems may be again divided into three classes, the first of which employs a battery at the central station for the purpose of supplying electrical energy; the second of which employs a continuously running generator, such as a dynamo or converter for supplying electrical energy; the third of which employs a generator of some description which is started before a call is made, and stopped after the call is made. If primary batteries are used in either of these systems, a large expense for maintenance arises, for, whether in use or at rest, a primary battery constantly deteriorates and it has been found that both the local energy systems and the central energy systems employing primary batteries, are exceedingly expensive and of the two, the local energy system is the more expensive. If secondary batteries are used, the expense of maintaining the batteries should be decreased, but on the other hand, when secondary batteries are used, a large initial outlay is needed to install charging apparatus therewith, and a further constant expense for the services of a skilled attendant to attend the batteries, so that the substitution of secondary batteries for primary batteries in a local energy system, although giving more satisfactory results as far as operation is concerned, is really more expensive than the use of primary batteries. In central energy schemes, secondary batteries have been substituted for primary batteries with much better results, but due to the fact that a comparatively high voltage must be impressed upon the line wires of the system at the central station a large number of batteries must be installed, which necessitates a very large initial outlay and because of the fact that the amount of current required to operate the system is very slight, the batteries are not discharged often enough to keep them in good condition, so that they deteriorate more rapidly than is sanctioned by good engineering practice.

If a generator is used in the central energy systems, it must be of such a type and be designed so rugged, that it may be run continuously 24 hours of the day and every day in the year, which, to one skilled in the art means almost an impossibility, so that it is readily understood that duplicate apparatus must be installed which, of course, necessitates a very large initial outlay. If a converter is used, operated by current derived from a commercial line, duplicate apparatus does not entirely solve the difficulty for the means to furnish current to the line may also fail. It has also been found that in such a system, the continuously running apparatus must have skilled attention, and as the ordinary operator employed in a selective signaling system does not have the necessary skill, some other person must be employed to care for the apparatus, thus increasing the cost for maintenance.

Systems employing an intermittently running generator would seem to be the most practical method of operating a selective signaling system, but in practice such systems have been found to be more objectionable than any of the others, for in making a call, employing such a system, three operations are necessary, first; the generator must be started and allowed to obtain sufficient speed to generate sufficient voltage; second, call must be sent, and third, the generator must be stopped. In practice it has been found that the first step is very often neglected and as a consequence much loss of time ensues and tempers are not improved, and it has also been found that unless strict watch is kept upon the operators they will neglect to stop the generator after the call has been made in order to do away with the necessity of starting the generator before the next call. When such "tricks" are resorted to, the system and apparatus suffers severely for the generator not being designed to run continuously, soon wears out and has to be replaced, and furthermore, the cost for electrical energy is very greatly increased so that it approaches very closely to those systems using the continuously running generator. Another difficulty with this system, when the generator is allowed to run continuously, arises from the fact that the generator not being designed to run continuously and therefore not furnished in duplicate, as soon as it wears out or breaks down, throws the entire system out of operation. As a general conclusion it may be said that it has been found to be desirable in systems designed for continuous uninterrupted operation where electrical energy is employed to, if possible, depend in the last instance upon batteries.

In the case of systems governing the movements of trains, which must act uninterruptedly and continuously all of the time,

it has been found by experience extending over long period of time, that for continuous and uninterrupted operation, reliance had best be placed upon batteries for furnishing electrical energy and for the same reason, a selective system which must also operate continuously and uninterruptedly, should depend for its source of energy upon batteries, but at the same time the number of batteries should be such that they will be obliged to furnish sufficient current to keep them in proper condition.

Applicants have, therefore, devised a system of selective signaling of such a character that batteries will be depended upon for a supply of electrical energy and the batteries are employed in such number as to be economical.

The principle underlying applicants' invention will be hereafter fully explained and the concrete physical embodiment by which applicants' principle can be practically applied, will be explained in such full, clear and concise manner that any one skilled in the art may readily understand the same and in order to have a more ready comprehension of the invention, applicants have supplemented the description by full and complete drawings, in which like characters of reference designate similar parts and in which:

Figure 1, is a plan view of the individual calling key, with some parts broken away. Fig. 2, is a front elevation of the individual calling key. Fig. 3, is a side elevation of the individual calling key looking in the direction of the arrow *a*, Fig. 2. Fig. 4, is a cross-sectional elevation on the line A—B, of Fig. 3, looking in the direction of the arrow *b*. Fig. 5, is a cross-sectional elevation on the line A—B, of Fig. 3, looking in the direction of the arrow *c*. Fig. 6, is a rear elevation of the individual calling key. Fig. 7, is a cross section on the line C—D, of Fig. 2. Fig. 8, is a diagrammatic view showing the system employing the individual calling key.

Construction.—1, designates a back mounting plate, and 2, designates a front mounting plate, the two plates being separated by the spacing sleeves 3, 4, which, at their forward ends have a reduced portion which passes through the front plate and also forms a shoulder for the front plate to bear against, and have a shoulder 5 and 6 respectively, formed thereon, against which the back plate 1, abuts, the sleeves being reduced at this point and extending rearwardly of the back plate any desired distance, such that the key may be spaced from a supporting wall the desired amount, and may be attached to a supporting wall by the screws 7 and 8, which pass through the sleeves 3 and 4 respectively, and are screw threaded upon their inner ends to engage with a screw

threaded member upon the supporting wall. The back plate 1 and the front plate 2, are further separated by the members 9 and 10, which extend therebetween and are reduced 5 in size on the forward end so as to form a shoulder against which the front plate bears, and which have a reduced portion passing through the front plate which is made of such a length that it may be upset so as to 10 form a rivet head, to hold the members 9 and 10 rigidly to the front plate and which is drilled and tapped in its rear end to receive screws 19 and 20, to hold the back plate firmly thereto; a shaft 11 passes through 15 both the front and the back plates through the holes formed therefor and bears on its outer end a cross piece 14, to which are attached two knobs 12 and 13, a screw 15 fastening the cross piece rigidly to the shaft; 20 and a short distance in front of the front plate the shaft bears a metallic sector 16, which has rigidly attached thereto a collar 17, both the sector and the collar having a hole therethrough, through which the shaft 25 passes and the collar has two holes drilled from the periphery thereof to the center hole, which two holes are screw threaded and adapted to receive 2 round head cap screws 18, which, when sufficiently screwed 30 in, bear against the shaft 11 and hold the sector in adjusted position; between the sector and the front plate, a collar 21 is placed which collar has a hole therethrough, through which the shaft 11 passes and has 35 a pin 22 rigidly inserted therein so as to extend diametrically from the center of the shaft.

23 designates two round head cap screws which are screwed into drilled and tapped 40 holes in the collar and which, when sufficiently screwed in bear against the shaft 11 and hold the collar 21 in adjusted position. Between the front and back plates 1 and 2, the shaft 11 has rigidly attached thereto, the 45 sleeve 24 by means of the pin 25, the forward end of the sleeve being reduced and the forward end of the reduced portion bears against the back side of the front plate 2, so that co-acting with sleeve 21, bearing 50 against the front of the plate 2, and which can be rigidly screwed to shaft 11, a means is provided for preventing longitudinal movement of the shaft 11; disk 26 is mounted upon the sleeve 24 and bears against the 55 shoulder 27 thereof, and serves to keep the spiral spring 28 in place, the inner end of the spiral spring having a hole therethrough, through which the pin 25 extends and the outer end having a loop formed therein and 60 passed about the member 9, best shown in Fig. 5, the end forming the loop being bent back upon itself and riveted to the main spring by means of the rivet 29, best shown in Fig. 5. Intermediate the ends of the 65 sleeve 24 is an enlargement 30, the periphery

of which is cut into the form of ratchet teeth, best shown in Fig. 4, and a pawl 31 pivoted on a stud rigidly attached to gear 33, is adapted to engage with the said ratchet wheel, being pressed into engagement therewith by reason of the spring 34, one end of which is attached by means of pins 35 to the wheel 33, the other end of which bears against the pawl, all as best shown in Fig. 4. The gear wheel 33 has a 70 hole through the center thereof which fits upon a hub on the sleeve 24 in such manner that it may rotate freely thereon, but is restrained from longitudinal movement thereon by abutting against the shoulder 36 on 75 one side and by reason of the disk 37 fastened thereto by means of a screw 38 on the other side, the said disk having a hole therethrough which allows the sleeve 24 to pass therethrough and to rotate therein, but is 80 prevented from longitudinal movement by reason of the collar 39, all as best shown in Fig. 7. By reference to Fig. 4, it will be seen that gear wheel 33 meshes with pinion 40, which is rigidly attached to a gear wheel 85 41, fastened to a shaft 42, journaled in the front and back plates 1 and 2; said gear wheel 41 meshing with the pinion 43 which is rigidly attached to the gear-wheel 44, 90 fastened to the shaft 45, journaled in bearings in the front and back plates 1 and 2; the gear wheel 44 meshing with pinion 46, 95 which is rigidly attached to gear wheel 47, which meshes with a pinion 48, the gear wheel 47 being fastened to a shaft 49 journaled in bearings in the front and back plate, the pinion 48 being rigidly attached to a shaft 50, which passes through the back plate 1 and has a cross piece 51 attached thereto by means of the screw 52; 53 designates 100 weights attached by means of pins 54 to each end of the cross-arm 51 in such manner that they may move freely in and out toward the shaft 50 and adapted to bear against the inside face of a cup 55 attached 105 to the back plate 1.

The shaft 42 extends through the front plate 2 and bears a sleeve 56, which is fastened thereto by means of screws 57; 58 designates a pin fastened to the sleeve 56 110 and projecting therefrom, best shown in Fig. 3, so that it will lie in the path of pin 22; 59 designates a contact disk having teeth 60 in the periphery thereof, best shown in Fig. 2, which has a hole through the center 115 adapted to receive a reduced extension of sleeve 56; 61 designates a ring contact disk, best shown in side elevation in Fig. 3, and in front elevation in Fig. 2, which has a hole therethrough adapted to receive the 120 reduced extension of the sleeve 56; 62 designates a washer; 63 designates a contact disk best shown in side elevation in Fig. 3, and in front elevation in Fig. 2, having teeth 64 on the periphery thereof and having a 125 130

hole through the center thereof adapted to receive the reduced portion of sleeve 56; 65 designates a nut which is screwed upon the reduced extension of sleeve 56 so as to clamp members 59, 61, 62 and 63 firmly together and against the shoulder on sleeve 56 existing by reason of the reduced portion; 66 designates a block of insulating material fastened to the front plate 2 and bears a spring 67 adapted at proper times to contact with disks 59 and 61; spring 68 which is adapted to contact with disk 63 and spring 69 which is adapted to contact with sector 16, all of the springs being firmly attached to the insulating block 66 by means of the screws 70; the springs each have a hole through their right hand end as viewed in Fig. 2, which coincide with holes formed in the insulating block 66 and with fiber insulating bushings 71, best shown in Figs. 4 and 5 so that screws 72, 73 and 74 may be passed therethrough to connect the springs electrically with bars which may be placed back of the individual key; 75 designates stop pins best shown in Fig. 5 for preventing the spring 28 from expanding more than it should; 76 designates a stop which, at the proper time, the arm 22 is adapted to contact.

Referring to Fig. 8, 77 designates a source of current; 78 a relay coil having an armature 79; 80 designates the commutator of armature of a motor having a field 81 and brushes 82 and 83; 84 designates a collector ring mounted on the same shaft as commutator 80, and connected to the middle point of windings forming an armature mounted on the same shaft as commutator 80, which armature furnishes direct current through the brushes 90 and 91 from the commutator 89 attached to the ends of its windings; 85 designates a field winding for the armature which is connected to commutator 89 and which is separately excited from the battery 77; and an alternating current is generated, which is taken off of brush 86 bearing on collector ring 84 and passing through the condenser 87 to ground 88; 92 designates an armature controlled by the cores 93 and 94 of electromagnets and having rigidly attached thereto, so as to oscillate therewith the rod 95 which bears at its upper end an insulating knob 96, positioned between two springs 97 and 98, which springs are connected to the brushes 90 and 91 and in the normal position are as shown, but when moved either to the right or to the left, make contact with points 99, 101, 100 and 102, the said points being connected through the reactance coils 103, 104, 105 and 106 to the two line wires 107 and 108, and being connected together by condensers 109 and 110; 111 and 112 designate the cores of a selector such as described in our co-pending application Serial #596,252 filed December 8, 1910; 113 designates the armature adapted to coöperate with said cores oscillating about the knife edge bearing 114, bearing the arm 115, which has attached at its upper end the two dogs 116 and 117, 70 adapted to contact with the two sectors 118 and 119 to rotate them independently and separately about the shaft 120, the sectors being held in the moved position by dogs 121 and 122; 123 designates a pin attached to 75 sector 118, which, when sector 118 has been moved sufficiently, contacts with springs 124 and moves it into contact with spring 125; 126 designates two coils which are wound upon the same core but in opposite directions so as to constitute a non-inductive resistance; 127 and 128 designate contact arms which are pressed into contact with points 129 and 175 when the sectors 118 and 119 have been properly actuated, as fully explained in our co-pending application herein referred to; 130 designates a condenser; 131 a direct current bell; 132 and 133 the cores of an electromagnet which actuate an armature 134 to operate a bell-hammer 135, 90 which strikes when properly actuated, the gongs 136 and 137.

Operation.—The individual calling key itself is set in operation by turning the cross piece 14 in the direction of the arrow *d* as shown in Fig. 2, which operation causes sector 16 to immediately contact with spring 69 and to travel in contact therewith until the motion is stopped by the pin 22 contacting with stop 76; the result of turning the cross piece 14 in the direction of the arrow *d*, is to turn the shaft 11 in the same direction, which turning of the shaft 11, will cause the spring 28 to be tensioned as the inner end is fastened to the pin 25 and the outer end is fastened to the member 9; the turning of shaft 11 will also cause sleeve 24 to turn and also cause ratchet 30, best shown in Fig. 4, to turn in the direction of the arrow *d*, and as the teeth of the ratchet 110 are so formed that the pawl 31 is not driven by them when the ratchet is turned in said direction, the pawl will simply be moved outwardly by the passage of the teeth and pressed inwardly again by the action of spring 34 as the successive teeth pass by it; when, however, the pin 22 contacts with stop 76 and the cross piece 14 is released by the hand spring 28 being tensioned, causes a reverse turning, namely, in the direction of the arrow *e*, Figs. 2 and 4, so that the shaft revolving in the direction of the arrow *e*, will cause the ratchet toothed sleeve to also revolve in the direction of the arrow *e*, as it is rigidly attached thereto, and a tooth of the ratchet wheel 30 engaging with pawl 31 causes the gear 33, to which pawl 31 is attached by pin 32, to revolve in the direction of the arrow *e* and the gear 33, meshing with pinion 40, causes the same to 130

revolve, which causes shaft 42 to revolve with its attached contact disks 59, 61 and 63. The speed of rotation is governed by the weights 53 which, when rotating, bear 5 against the inner face of the cup 55 and the weights are rotated through a train of gears composed of 41 attached rigidly to shaft 42, to which the pinion 40 is attached, pinion 43, gear wheel 44, pinion 46, gear wheel 47, 10 pinion 48, shaft 50 and cross piece 51. The weights are of such a length and of such a value, that the train of gears will rotate at the desired speed, thus governing the rate of rotation of shaft 42 and its attached contact 15 disks.

When shaft 11 returns to normal position, rotating in the direction of the arrow *e*, Fig. 2, it rotates the shaft 42 in the direction of the arrow *f*, Fig. 2, and as by the 20 preliminary movement in the direction of the arrow *d*, of shaft 11, the pin 22 is moved out of contact with the pin 58, the sleeve 56 and shaft 42 are free to rotate in the direction of the arrow *f*, which they do, and in so 25 doing, the contact disk 59 bearing the teeth 60, passes over and contacts with the end of spring 67 in such a manner that each tooth makes a contact with the spring 67 so that by the passage of the teeth, contact 30 is alternately made and broken in a circuit on which the frame of the key is one side and the spring 67 the other. After the teeth 60 have completely passed the spring 67, the teeth 64 on the member 63 then contact 35 with and pass over spring 68 in the same manner, and for the same purpose, and after the teeth 64 have performed their function, the disk 61 then passes over spring 67 making contact therewith and just after the disk 40 61 passes beyond the spring 67, the pin 58 arrives at approximately its initial position as shown in Fig. 2, so as to contact with pin 22, which has also almost reached its initial position as shown in Fig. 2.

45 The length of time during which sector 16 is in contact with spring 69 can be very easily regulated by rotating the sector 16 to any desired position about the shaft 11 after first loosening the two round headed cap 50 screws 18. The period of time elapsing before teeth 60 make contact with spring 67, after shaft 11 begins to rotate in the direction of the arrow *e*, is easily governed by adjusting the position of the disk 59 upon 55 the reduced portion of the sleeve 56, which may be easily done by means of nut 65 and in the same way the contact disk 63 bearing the teeth 64 is rotatably adjustable about the sleeve 56 as is also disk 61.

60 As shown in Fig. 2, disks 59 and 63 each have 8 teeth formed in their periphery and so will each cause 8 makes and 8 breaks, but the number of teeth may be as desired, so that any desired number of makes and 65 breaks can be obtained and in practice in-

dividual keys are all made with 8 teeth on each of the disks 59 and 63, so that if any other desired combination is needed, teeth can be removed by filing or cutting on either the disk 59 or 63. If teeth are removed from disk 59, they should be removed commencing with tooth 138 and the disk 63 should be then rotated about the sleeve 56 so that tooth 139 is the space of two teeth or thereabout removed in the direction of the arrow *g*, Fig. 2, from the last remaining tooth on contact disk 59, then if any teeth are to be removed from disk 63, one should commence to remove them at the tooth farthest removed from tooth 139. As will be seen later, the length of the contact part on contact disk 61 governs the length of call and the length of call can be any desired time within the limit of the key by varying the length of the contact part of contact disk 61, and in case teeth should be removed from the disks 59 and 63, the disk 61 should be rotated about the sleeve 56 in the direction of the arrow *f*, Fig. 2, so that the end of the contact part of disk 61 should not be farther removed from the last tooth remaining on disk 63 than the space of 2 or 3 teeth or thereabout.

As will be seen later, the sector 16 governs the starting and stopping of a generator and it is desirable to have the generator stopped immediately after the contact disk 61 breaks contact with spring 67 so in case a large number of teeth are removed from disks 59 and 63 and contact disk 61 is rotated considerably in the direction of the arrow *f*, about sleeve 56, the sector 16 should be rotated about the shaft 11 in the direction of the arrow *e*, so that it will break contact with spring 69 when returning to normal position after being operated immediately after contact disk 61 has broken contact with spring 67.

In Fig. 8, two springs 67 are shown merely for the sake of clearness in describing the device; the arrow *d*, indicates the direction sector 16 is moved when turned by hand; the arrow *e*, designates the direction the sector 16 moves when returned by the power of the spring; the arrows *f*, indicate the direction of movement of disks 59, 63 and 61 when operating.

The manual movement of sector 16, in the direction of the arrow *d*, causes the same to contact with spring 69 which causes current to flow in the following path: battery 77, wire 140, wire 142, relay coil 78, wire 143, spring 69, sector 16, wire 144, wires 145, 146 and 147 to the other side of the battery energizing the relay 78 and causing the armature 79 to make contact with wire 148, whereupon current flows in the following path: battery 77, wire 140, wire 149, armature 79, wire 148, wire 150, field coil 81, wires 151 and 147 to the other side of the 125 130

battery, current also flowing from wire 148 to brush 82 through the commutator whose armature is 80, brush 83 to wire 151, so that the armature of the motor rotates and 5 causes a rotation of the armature to which commutator 89 and collector ring 84 are attached and at the same time a current flows from wire 148 through wire 152, field 85 and wire 153 to wire 151, so that the field 10 85 is energized and current is generated by the rotation of the armature bearing the commutator 89. As soon as the manual means for turning the sector 16 are removed, the sector 16 begins to return to normal 15 position, rotating in the direction of the arrow *e* by virtue of the tension of the spring 28 as heretofore described and causes disks 59, 63 and 61 to rotate in the direction of the arrow *f*, which soon causes the first 20 tooth on disk 59 to contact with spring 67, which causes current to flow in the following path: battery 77, wire 140, wire 154, wire 155, coil about core 93, wire 156, wire 157, spring 67, first tooth 60, disk 59, wires 25 158, 159, 145, 146 and 147 to the other side of the battery which causes the right hand end of the armature 92, as seen in Fig. 8, to be drawn to the core 93, which causes the insulating button 96 to be drawn to the left, 30 thereby causing spring 98 to contact with point 102 and allow spring 97 by its natural resiliency to contact with point 100 and as a current has been generated by a rotation 35 of the armature of the converter, current may be considered to flow from brush 91 to wire 160, spring 97, point 100, wire 161, through reactance coils 103 and 104 to wire 108 and through wire 108 to wires 162 and 163 to the coil about core 111, then by wire 40 164 to and through the left hand resistance 126 to the right hand resistance 126, through wire 165, coil on core 112, wire 166, wires 167 and 168 to wire 107 and then through wire 169 through reactance coils 105 and 45 106 and wire 170 and 171 to point 102, spring 98, wire 172 to brush 90, so completing the circuit and causing armature 113 to operate sector 118 one step forward. The passing of the first tooth 60 on disk 50 59 beyond spring 67 breaks the circuit through spring 67 and the coil on core 93, so that the armature 92 bearing the insulating button 96 returns to normal position and breaks the heretofore described 55 circuit through the selector at the remote station so that the armature 113 returns to normal position and the sector 118 remains in the moved position by virtue of the dog 121 engaging with the teeth thereon, but a 60 circuit is again soon formed as before by the contact of the second tooth 60 of disk 59 with the brush 67 so that sector 118 at the remote station is again moved forward one tooth and so on until all of the teeth 60 65 on the disk 59 have passed beyond the spring

67 and in this particular case we have shown disk 59 as bearing three teeth, the remaining possible teeth being shown in dotted line.

After the teeth 60 on the disk 59 have operated as heretofore described, the first tooth 64 on the disk 63 contacts with spring 68 and makes a circuit in which current flows as follows: battery 77, wire 140, wire 154, coil on core 94, wire 173, brush 68, first tooth 64 on disk 63, disk 63, wires 174, 145, 146, and 147 to the other side of the battery; the current in the just described path causes the left hand end of the armature 92 to be drawn toward the core 94 which causes the insulating button 96 to press against the spring 97, causing it to make contact with point 99 and at the same time allows spring 98, by its natural resiliency to make contact with point 101, so that a current flows from the generator in the following path: brush 91, wire 160, spring 97, point 99, wire 175, wire 170, reactance coils 106, and 105, wire 169, line wire 107, wires 168, 167 and 166 through the coil on core 112, wire 165, to the right hand resistance 126; to the left hand resistance 126; wire 164, coil on core 111, wire 163, wire 162, line wire 108, reactance coils 104 and 103, wire 161, point 101, spring 98, wire 172, and brush 90, thus completing the circuit. 95

It will be noticed that the current in the last described path, flows out from the central station on line wire 107 and returns by line wire 108, whereas the current which formerly actuated the selector as described, 100 flowed out on line wire 108 and returned by line wire 107, the result being that the polarized armature 113 is now attracted by the core 111 causing the sector 119 to be actuated by the dog 117, to move it forward 105 one step, and as soon as the first tooth 64 on disk 63 passes beyond spring 68, the armature returns to its normal position and the dog 122 holds the sector 119 in its moved position ready to be again actuated by the 110 passing of the next tooth 64 of disk 63 by the spring 68. Disk 63 has been represented as having 4 operative teeth, and the further possible number of teeth have been shown by dotted lines, so that the result of the circuits made and broken by disk 59 and the disk 63 is to advance the sector 118 three steps and the sector 119, four steps, which is assumed to be the combination necessary to so actuate the selector as represented so that 115 the springs 127 and 128 will make contact with the points 129 and 175 when the selector is actuated again by current sent over the line wire caused by disk 61 making contact with spring 67. 120

After all of the teeth 64 have performed their functions of contact with spring 68, the disk 61 then contacts with spring 67 forming a circuit in which current flows as follows: battery 77, wire 140, wire 154, wire 130

- 155, coil on core 93, wire 156, wire 176, spring 67, disk 61, wires 177, 146, and 147 to the other side of the battery, thus causing the right hand end of armature 92 to be attracted as before and cause the insulating knob 93 to push spring 98 in contact with point 102 and allow spring 97 to make contact with spring 100, so that current will again flow from the generator by means of 5 brushes 90 and 91 to the line wires and through the coils on the cores 111 and 112 of the selector and thus again actuate armature 113 so that its right hand end will be lifted toward core 112, thus causing the sectors 118 and 119 to be placed in a position as fully described in our copending application heretofore mentioned, that upon the ceasing of the current the dogs 121 and 122 will allow them to fall back to normal position and break the current between springs 127 and 128 and points 129 and 175 but while being held in such position by the passage of the contacting part of disk 61 over the spring 67, the contacts 127 and 128 will 10 be making contact with points 129 and 175 so that a current from the collector ring 84 will flow by means of brush 86 and wire 178, condenser 87 and ground 88 to ground 88 at the selector station through wire 179, coils 30 on cores 133 and 132 in series, wire 180, condenser 130, wire 190, spring 128, point 129, wire 191 to junction 192, then passing by a multiple circuit back to the two brushes 90 and 91 as follows: One circuit being left 35 hand resistance 126, wire 164, wire on core 111, wire 163, wire 162, line wire 108, reactance coils 104 and 103, wire 161, point 100, spring 97, and wire 160 to brush 91, wire on the armature to which commutator 40 89 is attached to collector ring 84, the second circuit being from wire 191 at the selector station to right hand resistance 126, wire 165, coil on core 112, wires 166, 167 and 168 to line wire 107, then to wire 169 45 and through reactance 105 and 106 to wires 170, 171, and point 102 to spring 98, and wire 172 to brush 90, through the wire on the armature of which 89 is the commutator, to the collector ring 84, so that the alternating current generated and transmitted by 50 means of the collector ring 84 and commutator 89 will pass through the alternating current bell, the armature of which is designated by 134 and the hammer of which is designated by 135 causing the same to ring at the same time the direct current generated by the converter will pass by means of brushes 90 and 91 to the bell 131, by the following path: brush 91, wire 160, spring 55 97, point 100, wire 161, reactances 103, 104, wire 108, wire 193, bell 131, wire 191, spring 127, point 175, wires 195, 196, 167 and 168 to line wire 107 and then to wire 169 and through reactance 105 and 106 to wires 170, 60 171, to point 102, to spring 98, to wire 172, 65 171, to point 102, to spring 98, to wire 172,

and the other brush 90, thus completing the circuit for the direct current which causes the bell 131 to ring.

The springs 124 and 125 constitute what are called the all stations call contacts and are so placed that if sector 118 is stepped forward a greater number of steps than are needed to step up any combination on the line, the springs 124 and 125 will be brought together thus causing the alternating current bells at every station to ring simultaneously for, as has been seen, the alternating current for ringing the alternating current bell comes into the selector station from the ground by means of wire 179 through coils 80 upon the two cores 133 and 132 through wire 180 and a condenser 130, and wire 190 to spring 128, but if springs 124 and 125 were connected, the bell could be made to ring without closing contact between point 85 129 and spring 128 for the current flowing in wire 190, could pass to wire 197 through spring 124, to spring 125, to wire 198, to junction 192 and thence back to the two brushes 90 and 91 by the paths heretofore 90 described.

A telephone 199 has been connected across the line wires 107 and 108 so that the attendant at the selector station may, upon the ringing of either the alternating current 95 bell, or bell 131, communicate with the operator at the central station, who may likewise have a telephone connecting across the line wires 107 and 108.

A clear understanding of the circuits heretofore described allows one to readily understand, that the bells at the selector station will ring as long as the contact part of contact disk 61 is in contact with spring 67, and that as soon as it breaks contact there 105 with, the bells cease to ring and the selector returns to its normal position at which time, as heretofore described, the individual calling key has again returned to the position of the parts as shown in Fig. 2 with the pin 110 100 22 resting against pin 58.

The individual calling key as heretofore described is, as its name implies, used simply for calling one of a number of selector stations and must be duplicated as far as the 115 greater part of its construction is concerned, for every remote selector station on the line being modified, however, only in so far as the disks 59, 63 and 61 are adjusted upon the shaft 42, as heretofore described, and in so 120 far as sector 16 is adjusted upon the shaft 11 to correspond therewith, and further, only in so far as the number of teeth on the disks 59 and 63 are concerned, it being obvious that if the combination of a selector station 125 is 5-6, the number of teeth on disk 59 will be 5 and the number of teeth on disk 63, will be 6; whereas, if the combination were 3-4, there would be three teeth upon disk 59 and 4 teeth upon disk 63, and it may further be 130

observed that with a possible range of 8 teeth upon each disk 59 and 63, the possible range of combinations is 64, which affords a range ample to provide for the greatest number of selector stations which might possibly be upon any one line.

It must now be readily seen that applicants have devised a system and an individual calling key therefor which does away with the numerous objections to both the so-called "local energy systems" and the so-called "central energy systems," for applicants, in order to operate their system successfully, need only a few cells of secondary battery in duplicate, as represented by 77, as the necessary voltage for operating the selectors at the remote stations is obtained by transforming the low voltage battery current into a current of higher voltage by means of the rotary converter as described, and by so using an intermittently operating converter a very small number of cells may be employed, but the objections heretofore made to an intermittently operating converter, have been done away with, for, in applicants' key, the first manual motion in sending a call, starts the converter and just enough time is allowed to elapse between the first making of the contact which starts the converter, before current is supplied to the line to operate the selectors for the converter to attain sufficient speed to furnish ample voltage to operate the selectors at the remote stations, furthermore, after once manually operating the key, no further attention is needed, for all of the time during which impulses are sent to the line, the converter is in operation, but immediately the impulses cease and the call has been sent, ringing the bells at the remote stations, the key, in and of itself, without any further attention or operation by the operator, causes the breaking of a circuit, which causes the converter to be deprived of current and, therefore, causes it to cease ringing, thereby doing away with the formidable objections heretofore made against such systems in which it was possible to forget or neglect to shut down the converter, after a call had been made.

Applicants having now disclosed the principle of their invention and having accurately described and illustrated a particular physical embodiment thereof, what we claim and desire to secure by Letters Patent, is:

1. In a calling key in combination, a part adapted to be operated manually, means operatively connected to said part adapted to generate an electrical current upon the initial movement of said part, means operated by the return of said part to normal, adapted for sending a predetermined number of impulses of electricity in two directions, and to send an additional impulse of definite

length in one of said directions, said first mentioned means adapted to continue the generation of electrical current until said impulse of definite length has been sent and to thereafter discontinue.

2. In a calling key, in combination, a part adapted to be operated manually, means actuated by said manual operation to return said part to initial position after being actuated manually, a generator, means actuated by said manual operation of said part adapted on the initial movement of said part to start said generator and continue said generator in operation until said part returns to normal, and means for governing the current generated by said generator, actuated by said part adapted to be operated manually.

3. In a calling key, in combination, a part to be operated manually, means adapted for returning said part to normal position after being operated manually, a generator, means adapted for starting said generator upon the initial movement of said part manually and for continuing said generator in operation until said part returns to normal, means also set in operation by said manual operation for sending a predetermined number of impulses in one direction from said generator, means also set in operation by said manual operation thereafter acting to send a further predetermined number of impulses from said generator in a reverse direction and means also set in operation by said manual operation thereafter acting to send a single impulse in said first direction.

4. In a calling key, in combination, a shaft, a handle on said shaft, a sector on said shaft, a contact spring in proximity to said sector, a spring having one end fastened to said shaft, a fixed member to which the other end of said spring is fastened, a ratchet wheel attached to said shaft, a pawl pivoted on a gear wheel revoluble about said shaft, a spring fastened to said gear wheel at one end and pressing said pawl into engagement with said ratchet at the other end, a pinion meshing with said gear wheel, a shaft on which said pinion is mounted, a hub fastened to said shaft, a disk having teeth adjustably mounted on said hub, a contact spring mounted in the path of said teeth, a second disk having teeth adjustably mounted on said hub, a contact spring in the path of said teeth, a third disk adjustably mounted on said hub and having a part in the plane of said second mentioned contact spring, a centrifugal governor, a train of gears connecting said second mentioned shaft with said governor, a stop on said hub and a stop on said first mentioned shaft adapted to contact at normal position, and a fixed stop adapted to contact with said stop on said shaft in reverse position.

5. In a calling key, in combination, a

source of current, a converter connected to said source in a partial circuit, means to complete said partial circuit by the initial operation of said calling key and to maintain said partial circuit completed until said key returns to normal.

6. In a calling key, in combination, a generator adapted to furnish current, line wires, a selector connected to said line wires at a remote point, and means interposed between said line wires and said generator adapted by a single manual movement to start said generator and to cause impulses of current to flow from said generator to said line wires a predetermined number of times, means thereafter acting to cause said current to flow in the reverse direction a predetermined number of times and means thereafter acting to cause said current to flow in said first direction.

7. In a calling key, in combination, a generator, means for operating said generator, a selector, line wires connecting said generator and said selector, means interposed in said line wires adapted to cause said means for operating said generator to act, and to cause the current generated by said generator to flow first a predetermined number of times in one direction, then a predetermined number of times in the reverse direction, and then once in the first named direction.

8. In an individual calling key, a generator, means to operate said generator, a selector, means connecting said generator and selector, said means including means operable by a single manual motion, to start said generator, control the flow of current from said generator to said selector, and keep said generator running until said means returns to normal position.

9. In a calling key, in combination, a generator, means for causing said generator to operate, a signal, line wires connecting said generator and said signal, means operable by a single manual motion interposed in said line wires adapted to operate said means for causing said generator to act, cause the current generated by said generator to flow to said signal, and keep said generator running until said means returns to normal position.

10. In a signal device, normally deenergized conductors, a source of current, a converter, a normally open circuit connecting said source and converter, a transmitting device operatively connected to the converter and to the conductors, a signal device governed by the transmitting device through the conductors, and means operated in unison with the transmitting device to cause the converter to start and remain running until said means returns to normal.

11. In a calling key, in combination, a generator, means for operating said generator, a selector, line wires connecting said

generator and said selector, means interposed in said line wires adapted to cause said means for operating said generator to act, and to cause the current generated by said generator to flow first a predetermined number of times in one direction, then a predetermined number of times in the reverse direction, and then once in the first named direction, said means operable manually by one motion.

12. In a calling key, in combination, a source of current, a converter, a selector, line wires connecting the converter and the selector, means interposed in said line wires adapted on its initial movement to reverse from normal to cause said converter to operate by current from said source and to continue operating until said means returns to normal, said means including a pole changing relay and so governing the current generated by said converter as to cause it to flow first in one direction in said line wires and then in the reverse direction and then in said first direction again.

13. In a calling key, in combination, a source of current, a converter connected to said source in a partial circuit, means to complete said partial circuit, by the initial operation of said calling key and to maintain said partial circuit completed until said key returns to normal line wires, a selector, means set in motion by the return of said first mentioned means to normal to cause the current generated by said converter to flow a predetermined number of times in one direction and then a predetermined number of times in a reverse direction, and then in said first mentioned direction again, through said line wires, said line wires connected to said selector, thus causing said selector to selectively operate.

14. A converter, a signaling device, conductors extending from said converter to the signaling device, a transmitter interposed in said connections adapted when operated in one direction only to modify the current generated by said converter, a source of current, connections from said source of current to said converter, and a normally open break in said circuit controlled by said transmitter.

15. In a signal system, a signaling device, a source of current, a converter connected to said source in a normally open circuit, conductors connecting said signaling device and said converter, a transmitter interposed in said conductors, and means governed by said transmitter to close said normally open circuit upon the initial movement thereof, said transmitter adapted to automatically return to normal position.

16. In a selective calling key, in combination, a source of current, connections to the source of current, line wires, connections to the line wires, means to connect said connections so that a predetermined number of

positive impulses of electricity will be sent in one direction to the second said connections and means thereafter operating to send a predetermined number of positive impulses in another direction to the second said connections.

17. In a selective calling device, means for starting generators, connections to line wires, means for governing the current produced
10 from one generator to impress an electro-motive force on the connections to line wires and to reverse the direction of flow after a

predetermined number of impulses are impressed and to thereafter impress a predetermined further number in the said reverse direction.
